DESIGN FOR A TABLE

Herman O. Huseby, Huntington Park, Calif.,
assignor of one-half to Earl T. Sausser, Cathedral City, Calif.

Application March 16, 1936, Serial No. 61,658

Term of patent 14 years

To all whom it may concern:

Be it known that I, Herman O. Huseby, a citizen of the United States, residing in Huntington Park, in the county of Los Angeles and State of California, have invented a new, original, and ornamental Design for a Table, of which the following is a specification, reference being had to the accompanying drawing, forming part thereof:

I claim:

The ornamental design for a table, substantially as shown.

HERMAN O. HUSEBY.
